Primary Examiner — Melanie H Tung*Assistant Examiner* — Lavone D Tabor(74) *Attorney, Agent, or Firm* — Collard & Roe, P.C.(57) **CLAIM**

The ornamental design for a dental cleaning head, as shown and described.

DESCRIPTION

FIG. 1 is front perspective view of a dental cleaning head showing our new design;

FIG. 2 is another front perspective view thereof;

FIG. 3 is a side view thereof;

FIG. 4 is an inverted view of the opposite side thereof;

FIG. 5 is a top end view thereof;

FIG. 6 is a bottom end view thereof;

FIG. 7 is a front view thereof;

FIG. 8 is a back perspective view thereof; and,

FIG. 9 is a back view thereof.

The broken lines and the areas within the broken lines illustrate portions of the dental cleaning head that form no part of the claimed design.

1 Claim, 4 Drawing Sheets# US D740,033 S
